UNITED STATES PATENT OFFICE

HUGH BRADY AND REGINALD M. BRADY, OF NEW YORK, N. Y.

AUTOMATIC GAS-BURNER CONTROL

Application filed April 15, 1927. Serial No. 183,962.

Our invention relates to new and useful improvements in fuel burners generally, although the invention relates more particularly to oil burners of that type used in oil 5 stoves and furnaces.

One of the important objects of our invention is to associate an electrical ignition circuit with a fuel burner whereby if the fuel controlling valve is open and the flame be- 10 comes accidentally extinguished, the circuit will automatically re-ignite the fuel and thereby avoid the known dangers resultant from the fuel controlling valve remaining open subsequent to the flame being extin- 15 guished.

Another important object of our invention is to control the ignition circuit by the fuel controlling valve whereby when the valve is opened the circuit will be closed but when 20 the valve is closed the circuit will be opened to avoid the unnecessary use of the battery current or other source of electrical energy.

A further object of our invention lies in mounting the thermostat, which automatically controls a switch in the ignition circuit, on the upper side of the burner for direct contact with the flame and to provide a guard for said thermostat whereby the latter will be protected against accidental injury. 25

With these and other objects in view which will more fully appear, the nature of the invention will be more clearly understood by following the description, the appended claims, and the several views illustrated in 30 the accompanying drawings.

In the accompanying drawings which illustrate one form of our invention:

Figure 1 is a plan view of a gas stove burner equipped with our invention,

40 Figure 2 is a side elevation thereof,

Figure 3 is an enlarged sectional view,

Figure 4 is a detail end elevation of the burner showing the thermostatic switch,

45 Figure 5 is a detail sectional view taken on the line 5—5 of Fig. 3,

Figure 6 is a diagrammatic view of the ignition circuit,

50 Figure 7 is a detail view showing the main switch of the circuit in open position,

Figure 8 is a similar view but showing the switch in closed position, and

Figure 9 is a perspective view of the movable member of the main switch.

Like reference numerals designate corre- 55 sponding parts throughout the several figures of the drawings.

Referring to the specific form shown in the accompanying drawings, I have illustrated a plurality of gas burners A which are connected to a common gas supply pipe B. 60 Each burner A includes a circular head 5 of hollow construction and a hollow neck 6, the head being provided with a hollow cross bar 7. The circular head 5 is provided with a 65 series of openings 8 for permitting the escape of gas from within the head, and the cross bar 7 is likewise provided with a series of similar openings 9. The neck 6 is connected to the main supply pipe B through the medium 70 of a connecting nipple 10 which is formed with a valve seat 11. A rotary valve 12 is associated with the seat 11 for controlling the supply of gas or other fuel from the main supply pipe B to the associated burner 75 A. The cross bar 7 is provided with a plurality of spaced upwardly extending lugs 13, 14 and 15 respectively, which are formed with alined openings 16, 17 and 18 respectively. Seated within the alined openings 80 16, 17 and 18 is a thermostat 19 which is preferably formed of an elongated bar of metal such as brass. One end of this thermostat is fixedly secured to the lug 13 by means of a set screw 20, and the other end 85 of said thermostat projects outwardly beyond the lug 15 and carries at its extreme end a contact point 21. Thus the thermostat 19 is disposed directly above the burner A and is located in the direct path of the flames from 90 the cross bar 7. Fixed to the head 5 of the burner but insulated therefrom is a fixed contact 22 which is adapted to be engaged by the movable contact 21 when the thermostat 19 contracts. When the thermostat 19 95 expands, and consequently lengthens longitudinally under the influence of heat from the burner, the movable contact 21 will become separated from the fixed contact 22. The thermostat and the switch 21—22 which 100

is controlled thereby forms a part of an ignition circuit which includes a battery or other source of electrical energy. A wire 24 leads from the battery to the primary winding 25 of a spark coil 26, and a wire 27 leads from the primary winding 25 to the ground. Fixed to the valve 12 is a movable switch contact finger 28 which is adapted to be moved upon turning of the valve into engagement with or out of engagement from a pair of fixed contacts 29 and 30. These contacts 29 and 30 are insulated from each other and are supported by the end of the neck 6 adjacent the valve 12 through the medium of an insulating block 31. A wire 32 extends from the fixed contact 22 of the thermostatic controlled switch to the fixed contact plate 30. A wire 33 extends from the fixed contact plate 29 to the battery 23. A wire 34 is connected to the thermostat 19 and to the ground. The secondary 35 of the spark coil 26 includes terminals 36—36 forming therebetween a spark gap 37, the terminals 36 being supported by and insulated from the burner A, and the spark gap 37 thereof being located directly above one of the openings 9 formed in the cross bar 7.

As a result of the above construction, when the valve 12 is opened to permit gas to enter the burner A from the supply pipe B, the switch 28, 29 and 30 will be closed, and consequently current will flow from the battery 23 through the primary 25 of the spark coil 26, thence through the wire 27 to the ground, thence through the wire 34 to the thermostat 19, thence through the closed switch 21—22, thence through the wire 32 to the main switch 28, 29 and 30, and thence through the wire 33 to the battery, thus completing the circuit. The secondary winding 35 of the spark coil 26 will thereby produce a spark in the spark gap 37 and thereby ignite the gas flowing outwardly from the openings 9 in the burner. The flame having direct contact with the thermostat 19 will heat the latter and expand longitudinally and open the switch 21—22, thus breaking the ignition circuit. As a result, the battery 23, or other source of electrical energy, will not be needlessly used. Should the flame become extinguished while the valve 12 is still open, the thermostat 19 will contract and close the switch 21—22 thereby producing sparks in the spark gap 37 and causing the gas to be re-ignited automatically. By controlling the switch 28, 29 and 30 by the fuel supply valve 12, the ignition circuit will be opened whenever the valve 12 is turned to cut off the supply of fuel and consequently current from the battery 23 will not be needlessly used.

Projecting upwardly from the lugs 14 and 15 are projections or pins 38 and 39 respectively. A guard plate 40 is supported above the thermostat 19 by the lugs 13, 14 and 15.

The lugs 14 and 15 are respectively provided with upstanding pins 38 and 39, and the guard is formed with openings to receive the screw 20 and the pins 38 and 39. The guard is formed with a plurality of perforations 41 to permit the flame and heat therefrom to pass upwardly through the guard. The guard is relatively long and narrow and fully protects the thermostat 19 and associated switch 21—22 from contact with utensils and consequent damage.

It is of course to be understood that the details of structure and arrangements of parts may be variously changed and modified without departing from the spirit and scope of our invention.

We claim:

1. The combination with a gas burner, of an ignition circuit including a thermostat, a switch controlled thereby and a spark gap, the thermostat being mounted on the burner for direct contact with the flame for automatically opening the switch under the influence of the heat from the flame and for automatically closing the switch upon failure of said flame, and a guard supported by the burner above the said thermostat to protect it from injurious contact and being cupped over the thermostat to tend to hold the flame in contact with said thermostat.

2. The combination with a gas burner, of an ignition circuit including a thermostat, a switch controlled thereby and a spark gap, the thermostat being mounted on the burner for direct contact with the flame for automatically opening the switch under the influence of the heat from the flame and for automatically closing the switch upon failure of said flame, and a guard-supported by the burner above the said thermostat to protect it from injurious contact and having a portion extended over the spark gap in relatively close cupped relation to tend to entrap escaping gas and facilitate ignition of the burner.

3. The combination with a gas burner, of an ignition circuit including a thermostat, a switch controlled thereby and a spark gap, the thermostat being mounted on the burner for direct contact with the flame for automatically opening the switch under the influence of the heat from the flame and for automatically closing the switch upon failure of said flame, and a guard supported by the burner above the said thermostat to protect it from injurious contact and being cupped over the thermostat to tend to hold the flame in contact with said thermostat, said guard also having a portion extended over the spark gap in relatively close cupped relation to tend to entrap escaping gas and facilitate ignition of the burner.

4. The combination with a gas burner including an elongated burner portion having a row of aligning gas discharge apertures.

and means to feed gas to the apertures including a control valve of an ignition circuit including a thermostat, a switch including movable and stationary contacts controlled by said thermostat and a spark gap positioned in associated relation with one of the burner apertures, a plurality of lugs upstanding from the elongated burner portion in alignment with the row of apertures and themselves having aligning apertures, said thermostat comprising an elongated element adapted to be extended and contracted longitudinally under influence of the gas flame or due to the absence thereof respectively and having one end secured to one lug and slideable through another lug while expanding or contracting, the movable contact of said switch being carried by the movable end of said thermostat, and a guard member supported upon the said lugs and cupped over the spark gap and the thermostat element to pocket the flame over the said element or to pocket escaping gas over the said spark gap.

In testimony whereof we hereunto affix our signatures.

HUGH BRADY.

REGINALD M. BRADY.
